CLAIM

The ornamental design for a chastity device, as shown and described.

DESCRIPTION

FIG. 1 is a top front right perspective view of a chastity device showing my new design;

FIG. 2 is a bottom front left perspective view thereof;

FIG. 3 is a bottom rear left perspective view thereof;

FIG. 4 is a top rear right perspective view thereof;

FIG. 5 is a front elevational view thereof;

FIG. 6 is a rear elevational view thereof;

FIG. 7 is a right elevational view thereof;

FIG. 8 is a left elevational view thereof;

FIG. 9 is a top plan view thereof;

FIG. 10 is a bottom plan view thereof;

FIG. 11 is a reduced top front right perspective view of the chastity device in an open configuration;

FIG. 12 is a reduced bottom front left perspective view in an open position thereof;

FIG. 13 is a reduced top rear right perspective view in an open position thereof; and,

FIG. 14 is a reduced bottom rear left perspective view in an open position thereof.
